US00D371113S

United States Patent [19]

Hubbell et al.

[11] Patent Number: Des. 371,113

[45] Date of Patent: **Jun. 25, 1996

[54] **INTEGRATED POWER DISTRIBUTION AND TRANSIENT VOLTAGE SURGE SUPPRESSION SYSTEM**

[75] Inventors: **Douglas P. Hubbell**, Coeur d'Alene, Id.; **Kenneth E. Morden**, Spokane; **Mark C. Willis**, Veradale, both of Wash.

[73] Assignee: **Northern Technologies, Inc.**, Liberty Lake, Wash.

[**] Term: **14 Years**

[21] Appl. No.: **38,722**

[22] Filed: **May 12, 1995**

[52] U.S. Cl. **D13/160**; D13/164

[58] Field of Search D13/123, 160, D13/184, 164; 361/600, 622, 628, 643

[57] **CLAIM**

The ornamental design for integrated power distribution and transient voltage surge suppression system, as shown and described.

DESCRIPTION

FIG. 1 is an isometric view of an integrated power distri-

bution and transient voltage surge suppression system; FIG. 2 is a front view of the integrated power distribution and transient voltage surge suppression system of FIG. 1;

FIG. 3 is a bottom view of the integrated power distribution and transient voltage surge suppression system of FIG. 1;

FIG. 4 is a top view of the integrated power distribution and transient voltage surge suppression system of FIG. 1;

FIG. 5 is a rear view of the integrated power distribution and transient voltage surge suppression system of FIG. 1;

FIG. 6 is a left hand side view of the integrated power distribution and transient voltage surge suppression system of FIG. 1;

FIG. 7 is a right hand side view of the integrated power distribution and transient voltage surge suppression system of FIG. 1;

FIG. 8 is an isometric view of the integrated power distribution and transient voltage surge suppression system of FIG. 1 with a cabinet door open;

FIG. 9 is a front view of the integrated power distribution and transient voltage surge suppression system of FIG. 8;

FIG. 10 is a bottom view of the integrated power distribution and transient voltage surge suppression system of FIG. 8;

FIG. 11 is a top view of the integrated power distribution and transient voltage surge suppression system of FIG. 8;

FIG. 12 is a rear view of the integrated power distribution and transient voltage surge suppression system of FIG. 8;

FIG. 13 is a left hand side view of the integrated power distribution and transient voltage surge suppression system of FIG. 8; and,

FIG. 14 is a right hand side view of the integrated power distribution and transient voltage surge suppression system of FIG. 8.
